STRUCTURAL ELEMENT

Markus Reiner, Jerusalem, Palestine, and Eugene C. Bingham and William S. Lohr, Easton, Pa.

Application May 9, 1933, Serial No. 670,060

15 Claims. (Cl. 72—75)

The invention provides an improvement whereby greater strength and economy is obtained in structural elements such as columns, pillars, arches and the like which are of greater length in one direction than in the other two directions, and are designed to take compressive forces in the longitudinal direction.

Such structural elements are used as parts of various devices, machines and structures. The improvements are particularly directed to structural elements composed chiefly of concrete or of other materials which are best adapted to resist compression.

By our improvements we secure a generally increased bearing capacity for a given size, or, conversely, economy in space and in cost by using a smaller element to carry a given load.

These objects are secured by encasing the concrete or the like in a shell which is specially adapted to carry tensile stresses; such as steel or metal, wood, paper, textile materials and other compositions, depending upon the uses to which the element is to be put, and the strains and other conditions to which it is to be subjected.

The parts are so arranged that the shell is subjected wholly or mainly to pressure acting in directions normal to its internal surface so as to produce stresses in tension only or mainly. The longitudinal compressive stresses on the core are not transmitted directly to the shell but are resolved into components in the direction stated.

The accompanying drawings illustrate embodiments of the invention, being, however, only a few of the various forms in which the principle may be applied.

Fig. 1 is a longitudinal section of a complete column;

Fig. 2 is a cross-section of the same;

Fig. 3 is a cross-section of a similar column which is rectangular instead of circular;

Fig. 4 is a longitudinal section of a modification;

Fig. 5 is a longitudinal section of an arch;

Fig. 6 is a longitudinal section of a modified form of arch;

Fig. 7 is a cross-section of the arch of Fig. 5 near one end;

Fig. 8 is a longitudinal section of the lower portion of another modification.

Referring to Fig. 1, the column has a base member with a vertical flange 1 and a horizontal plate 2 which rests on the support 3. At the upper end there is a similar member forming a downward flange 4 and horizontal cap plate 5 for transmitting the load 9. The core 6 is of

concrete. This may be the usual concrete made of cement, sand and broken stone. It is encased in a steel shell 7.

The arch of Fig. 5 is on the same principle as the column of Fig. 1 with steel end pieces 1, 2 and 4, 5 at opposite ends for taking the thrust on the abutments 3.

The flanges 1 and 4 enter the shell 7 and confine the concrete in the short distance which is left between the ends of the shell 7 and the plates 2 and 5 respectively.

In the case of a circular section, the shell 7 is continuous as shown in Fig. 2. Where a rectangular section is used, as in Figs. 3 and 7, a correspondingly shaped shell is provided with angles 8 at the corners which stiffen the shell and may be used to join plates constituting the several sides.

In the case of Figs. 4 and 6, the construction is similar to that of Figs. 1 and 5, but omitting the end plates. There is a clearance between each of the ends of the casing 7 and the adjacent abutment. But this is so slight that it does not seriously impair the strength of the element.

It has been found that when concrete, either plain or with the ordinary reinforcement, is subjected to sustained compressive stresses, it shows a certain plasticity and permits considerable deformation, much in excess of the elastic deformation. This brings with it an over-stressing of the usual reinforcing steel rods, which may ultimately bring failure to the structure.

The usual method of reinforcing such concrete elements in compression has been based on considerations of purely elastic deformation and, therefore, cannot lead to stable and safe structures. Longitudinal steel reinforcing rods do not serve any substantial useful purpose in structural elements which are in pure compression. Plastic deformation can be prevented only by hindering the structural element from the lateral expansion which accompanies longitudinal shortening.

This is accomplished in the present invention by the encasing of the core in a steel shell. No other reinforcement is necessary. Hollow steel columns have heretofore been filled with concrete. But in that case the steel column carried the major part or a very considerable part of the longitudinal stresses and, therefore, was in danger of buckling. By providing for a slight play between the ends of the shell and the adjacent abutments, we eliminate longitudinal compressive stresses in the shell or reduce them to negligible quantities.

While it is possible to use a shell with small

openings which might lighten it and have other advantages, these openings must not be large enough to permit the extrusion of the core through them under its plastic yielding. Where we refer 5 to an "enclosing shell", we mean a shell which though not necessarily completely continuous, is such as to confine the core transversely at all points.

An advantageous feature of the invention is in 10 the construction which avoids the transmission of any substantial part of the longitudinal load to the shell. The shell is thus saved from any strain tending to buckle it. This may be accomplished by a sort of piston arrangement telescoping 15 with the shell and transmitting pressure directly to the core as in Fig. 1, or by merely leaving a gap or slight play between the ends of the shell and the abutments so that the latter bear only on the core as in Fig. 2.

20 The shell can be used as a form for the core, thus obviating the necessity of using ordinary concrete-pouring forms.

In order to protect the steel or other material of the shell from corrosion, or from the effects 25 of fire, any of the usual protective schemes may be used such, for example, as painting and rust-proofing, or covering with gypsum, terra cotta or other fireproofing material.

In order that the stresses imposed by the concrete on the shell shall be solely in the radial directions, normal to the inner face of the shell at the point of application, it would be necessary 30 to prevent adhesion between the core and the shell. Generally adhesion of the concrete to the steel will not be such as to materially affect the working out of the principles of the invention, and the concrete can be cast directly into the shell. However, the inside surface of the shell may be first covered with a coating 7^a (Fig. 8) of grease, 35 oil, asphalt, paint or some other material which lessens the adhesion to a determined limit, or may be covered with a layer of paper or the like for the same purpose.

The quality of the materials of which the core is 40 made is of secondary importance as long as the pore spaces are completely filled. This means great economy in the amount and quality of the cement used. The cementing medium, in fact, instead of being hydraulic cement may be a composition 45 which is more commonly recognized as viscous, such for example as asphalt and other bituminous compositions. Furthermore, the concrete may be made to carry a considerably higher working unit stress than heretofore, which means 50 a decrease in the cross-section and an economy in materials and floor space. The steel or other shell at the same time is used with its greatest economy because it is subjected mainly or wholly to tension and is not in danger of buckling.

55 Although no reinforcement of the concrete within the shell is necessary, such supplementary reinforcement may be used. Also the shell, instead of being of plain sheet metal, may be reinforced by making it of special shapes, or by the 60 application of supplementary reinforcements of any usual or suitable type.

Various modifications other than those described may be made by those skilled in the art without departing from the invention as defined 65 in the following claims.

What we claim is:—

1. A structural element for carrying longitudinal compression, comprising a core of material adapted to withstand compression and having a certain plasticity under sustained pressure and

80 a shell enclosing said core so as to prevent expansion of any substantial part thereof radially beyond the shell and formed of a material adapted to carry tensile stresses, the ends of the core in use being exposed to the external longitudinal pressures and the shell in use being exposed only to the radial pressures of the core within it.

2. The structural element of claim 1, in combination with plates at the ends of the core with inward flanges through which plates the longitudinal forces are transmitted to the core. 85

3. The structural element of claim 1, in combination with a coating of material between the core and the shell which is adapted to prevent or restrict the adhesion between the core and the shell. 90

4. A structural element for carrying longitudinal compression, comprising a core of concrete to the ends of which the external longitudinal forces are applied and an enclosing metallic shell, the core projecting at the ends beyond the shell so as to avoid transmission of longitudinal forces to the shell. 95

5. The structural element of claim 4, in combination with metallic plates at the ends of the core provided with inward flanges telescoping with the shell. 100

6. The structural element of claim 1, the core being molded within the shell.

7. A structural element for carrying longitudinal compression, comprising a core of concrete to the ends of which the external longitudinal forces are applied and an enclosing metallic shell, the core projecting at the ends beyond the shell so as to avoid transmission of longitudinal forces to the shell, the concrete of the core being made up of aggregate and a viscous material. 105

8. The structural element of claim 7 in combination with metallic plates at the ends of the core provided with inward flanges telescoping with the shell. 110

9. A structural element for carrying longitudinal compression, comprising a core of concrete to the ends of which the external longitudinal forces are applied and an enclosing metallic shell, the core projecting at the ends beyond the shell so as to avoid transmission of longitudinal forces to the shell, and a coating of material between the concrete and the shell which is adapted to prevent or restrict the adhesion between the core and the shell. 115

10. The structural element of claim 9, in combination with metallic plates at the ends of the core provided with inward flanges telescoping with the shell. 120

11. The structural element of claim 1, the core being molded within the shell, in combination with plates at the ends of the core with inward flanges through which plates the longitudinal forces are transmitted to the core. 125

12. The structural element of claim 4, the core being molded within the shell and consisting of aggregate and a viscous material.

13. The structural element of claim 4, the core being molded within the shell and consisting of aggregate and a viscous material in combination with metallic plates at the ends of the core provided with inward flanges telescoping with the shell. 130

14. The structural element of claim 1 in combination with an abutment, the end of the shell being separated by a certain play from the abutment and the end of the core having a direct 135

pressure-transmitting engagement with the abutment.

15. A structure including an element for carrying longitudinal compression, said element comprising a core of material adapted to withstand compression and having a certain plasticity under sustained pressure and a shell enclosing said core so as to prevent expansion of any substantial part thereof radially beyond the shell

and formed of a material adapted to carry tensile stresses, the core alone being subjected to the longitudinal pressures from the adjacent parts of the structure, and the shell being subjected only to the radial pressures of the core within it.
